UNITED STATES PATENT OFFICE.

JOHN W. STOKOE, OF JEANERETTE, LOUISIANA, ASSIGNOR OF ONE-HALF TO HENRY O. SCRANTON, OF JEANERETTE, LOUISIANA.

CAR-STAKE.

No. 865,448.

Specification of Letters Patent.

Patented Sept. 10, 1907.

Application filed May 4, 1907. Serial No. 371,838.

To all whom it may concern:

Be it known that I, JOHN W. STOKOE, a citizen of the United States, residing at Jeanerette, in the parish of Iberia and State of Louisiana, have invented a new 5 and useful Car-Stake, of which the following is a specification.

This invention relates to car stakes and its object is to provide simple and durable devices of this character designed to be secured to the sides of a car platform, and which, when not in use, can be swung and slid out of operative position.

Another object is to provide simple and efficient means for holding the stake either in raised or lowered position without the use of separate fastening means.

15 A still further object is to provide stakes which, by reason of their peculiar connections with their supports, can be caused to lap when in inoperative position, thereby permitting the stakes to be placed close together.

20 Another object is to provide stakes each of which constitutes a housing for a chain or similar flexible device, the devices within the several stakes being designed to be drawn outward therefrom and fastened across the platform.

25 With these and other objects in view the invention consists of certain novel features of construction and combinations of parts which will be hereinafter more fully described and pointed out in the claims.

In the accompanying drawings is shown the preferred form of the invention.

In said drawings: Figure 1 is a side elevation of a portion of a car having stakes thereon constructed in accordance with the present invention, certain of the stakes being in raised position and the stake supports being shown both in section and elevation; Fig. 2 is a longitudinal section through one of the stakes and its support; Fig. 3 is a section on line $x-x$, Fig. 4; Fig. 4 is a section on line $y-y$, Fig. 3; and Fig. 5 is a section on line $z-z$, Fig. 4, the stake being shown in 40 elevation.

Referring to the figures by characters of reference, 1 designates a car platform and secured to each side thereof at desired intervals apart are supports 2 each of which is preferably held in place by means of bolts

45 3. Each of these bolts is formed of heavy metal and has oppositely disposed, substantially sectoral recesses 4 formed therein and communicating at the center of the support where a central stop lug 5 is located. One of the walls of each recess is perpendicular to the top 50 of the car platform as shown at 6 and these two walls are located in planes spaced apart a distance equal to the width of the car stake which will be hereinafter described.

The opposite walls 7 of the two recesses are disposed at angles of about one hundred degrees to the top of the 55 platform although it is to be understood that this angle may be varied to suit different conditions. These two walls are also located in places which are spaced apart a distance equal to the width of the stake. The lower recess 4 is partly closed at the periphery of the 60 support by an arcuate wall 8, there being an opening 9 formed between the lower end of the wall and the vertical wall of the lower recess and another opening 10 between the upper end of the arcuate wall and the adjoining wall of the lower recess. Opening 10 is equal 65 in width to the width of the stake hereinafter described, whereas the opening 7 is of less width. The walls 6 and 7 of the two recesses are grooved longitudinally as indicated at 11 and the inner curved face of the arcuate wall 8 is also curved as shown at 12. The walls 70 of the opening 9, however, are not grooved but instead form abutments 13 for the purpose hereinafter described.

The stake 14 used in connection with each support 75 consists of an elongated metallic member formed with ribs 15 which extend longitudinally along the sides thereof and are designed to fit within the grooves 11. These ribs terminate short of the lower end of the stake and said end is reduced in thickness to form a tongue 16. A groove 17 is formed longitudinally within one 80 face of the stake and the stop lug 5 projects thereinto and therefore serves to limit the longitudinal movement of the stake. The groove is so located and proportioned as to permit the tongue 16 to be raised out of opening 9 and to travel within groove 12, and also to permit the 85 stake to be moved longitudinally through the opening 10 until the lug 5 assumes a position at the center of the stake. A passage 18 is formed longitudinally within the stake and opens through the lower end thereof and also through the inner face of the upper portion 90 of the stake. Within this passage is slidably mounted a chain 19 having a weight 20 at one end, while its upper end projects through the inner face of the stake and is provided with a hook 29 or other suitable device whereby the chain may be fastened to a similar one located at the opposite side of the car.

The supports 2 are designed to be secured to the sides of the platform 1, the distances between them being about one-half the length of the stakes. The parts are so proportioned that when the stop lugs 5 are in contact 100 with the upper ends of the grooves 17 the stakes lie in inclined positions with the sides of the platform, the upper halves of the stakes lapping the lower halves of the adjoining stakes. When the stakes are thus positioned their upper ends are below or flush with the 105 top of the platform, as shown in Fig. 1. When it

is desired to raise a stake so that the same can be used for retaining a load upon the platform, the stake is drawn longitudinally until the lug 5 contacts with the lower end of groove 17. The stake is then swung upward and tongue 16 will travel within the curved groove 12 until it assumes a position above the opening 9. The stake will then move downward by gravity with the reduced end thereof within the opening 9 and this downward movement will be stopped by the ends of ribs 15 coming into contact with the abutments 13. Hook 21 can then be pulled across the platform carrying the weighted chain therewith, and can be fastened to a similar hook extending from a stake at the other side of the platform. When the hooks are released the weights will return the chains to their normal positions whereupon the stake can be lowered by reversing the operation hereinbefore described.

What is claimed is:

1. The combination with a fixed support having oppositely disposed communicating sectoral recesses and a projecting device within the support and at the point of communication between the recesses; of a stake slidably mounted within the recesses and disposed to swing therein to assume an upright or a non-upright position, said stake having a longitudinal groove into which the projecting device extends, said support having an aperture to receive one end portion of the stake to hold it when in an upright position.
2. The combination with a fixed support having oppositely disposed communicating sectoral recesses, and a

projecting device within the support at the point of communication between the recesses; of a stake slidably mounted within said support and disposed when partly withdrawn therefrom to swing within the recesses to assume an upright or a non-upright position, said stake 35 having a longitudinal groove into which the projecting device extends to limit the longitudinal movement of the stake, said support having means to hold the stake when in an upright position and to prevent the swinging movement thereof when extending through the support in a 40 non-upright position.

3. The combination with a fixed support having oppositely disposed communicating sectoral recesses, and a projecting device within the support at the point of communication between the recesses; of a stake slidably 45 mounted within said support and disposed when partly withdrawn therefrom to swing within the recesses to assume an upright or a non-upright position, said stake having a longitudinal groove into which the projecting device extends to limit the longitudinal movement of the stake, said support having means to hold the stake when in an upright position and to prevent the swinging movement thereof when extending through the support in a 50 non-upright position, and a weighted flexible device normally housed within the stake and disposed to be partly 55 withdrawn therefrom.

In testimony that I claim the foregoing as my own, I have hereto affixed my signature in the presence of two witnesses.

JOHN W. STOKOE.
